**SOLVENT REFINING OF NAPHTHENIC LUBE
OIL WITH N-METHYL-2-PYRROLIDONE**

ABSTRACT OF THE DISCLOSURE

Manufacture of naphthenic lubricating oil product by distillation of crude oil containing naphthenic lubricating oil effecting separation of the naphthenic lubricating oil stocks; refining lubricating oil stocks for removal of constituents of low viscosity index, low thermal stability, and poor oxidation stability by solvent extraction with an aqueous solvent phase comprising between about 85 and 98 wt. percent N-methyl-2-pyrrolidone and between about 2 and 15 wt. percent water at conditions effective to dissolve at least 10 vol. percent producing as a raffinate a refined lubricating stock of said lubricating oil stocks of improved viscosity index, thermal stability and oxidation stability.

BACKGROUND OF THE INVENTION

In the manufacture of naphthenic lubricating oil from crude petroleum one or more fractions containing the naphthenic lubricating oil constituents are separated by distillation, usually by vacuum distillation. The raw lubricating oil fractions contain unstable naturally occurring materials which tend to form deposits or become corrosive in operating equipment as a result of heating and oxidation or both. Additionally, it is often desirable to increase the viscosity index of the lubricating oil by removing the more aromatic lower viscosity index constituents from the oil. To accomplish this it is necessary to remove or destroy a significant amount of material present in the raw stock, typically ranging from 10 to 60 percent depending on the qualities desired in the product oil. The most common way to do this is by extraction with a solvent having selectivity for the more unstable molecules which are predominantly aromatic and nonhydrocarbon materials. Prior to the advent of solvent extraction, severe treatment with concentrated sulfuric acid was commonly used to destroy these undesirable materials.

In the treatment of oils to remove unstable, corrosive and low viscosity constituents of oil, a substantial amount of material is removed from the charge stock, that is, an amount in excess of about 10 volume percent. This is distinctly different from decolorizing treatment in lubricating oil manufacture where only trace amounts of coloring material are removed, typically less than 1.0 percent. Such color improvement steps are often used after solvent refining. A raw stock that is only treated for color improvement is usually unsatisfactory as regards thermal and oxidation stability or viscosity index.

This invention is particularly directed to the solvent extraction step in the manufacture of naphthenic lubricating oils by the sequence of distillation, solvent extraction, solvent dewaxing (optional) and blending. Broadly, the solvent extraction in the invention is accomplished with aqueous N-methyl-2-pyrrolidone at a temperature of at least 50° F. and below the temperature of complete miscibility of the lubricating oil stock in N-methyl-2-pyrrolidone and at a dosage effective to dissolve at least 10 volume percent of said lubricating oil stock whereby a refined lubricating oil stock is produced of improved viscosity index, improved thermal stability, and improved oxidation stability.

2

Heretofore, anhydrous and essentially anhydrous, N-methyl-2-pyrrolidone has been known as a solvent for the separation of constituents of low thermal and oxidation stability from lubricating oil fractions and for the separation of low viscosity index constituents from lubricating oil. However, when naphthenic oil is the lubricating oil to be refined several unexpectedly undesirable factors arise in the refining process using anhydrous and essentially anhydrous N-methyl-2-pyrrolidone. Specifically, in the case of naphthenic residual stocks there results high miscibility of the stock in the solvent and relatively high viscosity of the refining mixture, particularly when low solvent dosage, e.g., between about 50 and 150 vol. solvent/100 vol. crude oil, and solvent extraction temperatures above 100° F. are employed. Further, in respect to the naphthenic residual stocks and distillates, a low yield of refined oil results from the high solvent power of N-methyl-2-pyrrolidone.

Hereinbefore and hereinafter, the term "essentially anhydrous" means a water content of zero to less than about 1 wt. percent.

SUMMARY OF THE INVENTION

In accordance with this invention, finished naphthenic lubricating oils are produced from naphthenic base crude oil by vacuum distillation, solvent refining of the vacuum distillate or residual stock with aqueous N-methyl-2-pyrrolidone as a selective solvent and optionally inhibitor addition. We have unexpectedly discovered in the solvent refining step, by incorporating between about 2 and 15 wt. percent water basis total solvent in the N-methyl-2-pyrrolidone, undesirable miscibility, increased viscosity and low refined oil yield are avoided.

DETAILED DESCRIPTION OF THE INVENTION

Specifically, in the solvent refining step, the vacuum naphthenic distillate or residual naphthenic lubricating oil stock is contacted with N-methyl-2-pyrrolidone having a water content of between about 2 and 15 wt. percent, preferably between about 3 and 10 wt. percent, at a temperature of at least 50° F. and below the temperature of complete miscibility of said naphthenic lubricating oil stock in N-methyl-2-pyrrolidone and at a dosage effective to dissolve at least 10 volume percent of said lubricating oil stock. The foregoing solvent extraction step produces a refined lubricating oil stock of improved viscosity index, improved thermal stability and improved oxidation stability. The manufacture of a merchantable naphthene base lubricating oil does not require dewaxing and only the addition of usual inhibitors is necessary.

Specific examples of naphthenic oil contemplated herein are oils used in the manufacture of turbine lubricating oils of an SUS viscosity at 100° F. of between about 100 and 600; refrigeration oils of an SUS viscosity at 100° F. of between 80 and 600; and cylinder oils of an SUS viscosity at 100° F. of between 1000 and 4000. Typically, the viscosity index of naphthenic base lubricating oil charge stocks is within the range of about —10 to 50 and the viscosity index of the refined lubricating oil stock is at least 10 units higher.

The extraction temperatures and dosages in refining naphthene oils are advantageously within the range of 50 to 200° F., preferably within the range of 75 to 150° F. and 30 to 300%, and preferably 75 to 200% respectively.

A typical processing sequence which may be used in the manufacture of lubricating oils in accordance with the process of this invention is crude naphthenic oil is passed to crude distillation facility. In the crude distillation facility the crude oil is separated into lower boiling fractions, for example gas and fuel distillates and gas oils, medium

boiling fraction such as naphthenic lubricating oil distillates and crude residuum. The lubricating oil naphthenic distillate and/or naphthenic residual lube stock is passed to aqueous N-methyl-2-pyrrolidone solvent extraction facility wherein the lubricating oil distillate and/or stock is contacted with aqueous N-methyl-2-pyrrolidone resulting in separation of an extract comprising solvent and solvent soluble materials and raffinate comprising solvent refined lubricating oil. The extract and raffinate are separated and the lube oil raffinate is optionally combined with standard corrosion and/or oxidation inhibitors as well as the standard detergent-dispersants (if required) in a subsequent lube oil product blend.

Standard apparatus and distillation, blending and separation techniques are applicable to the subject method.

EXAMPLE I

This example demonstrates the method of the invention and the criticality of using water to modify the solvent power of N-methyl-2-pyrrolidone to permit control of refined oil quality and yield.

In a specific application of this invention, a residual naphthenic lubricating oil stock is separated from crude oil by vacuum distillation. The naphthenic oil stock is extracted in a 12-stage countercurrent mixer-settler extraction apparatus using N-methyl-2-pyrrolidone having varying water contents. The conditions and results are set forth below in Tables I and IA:

EXAMPLE II

This example demonstrates the method of the invention and the advantage of maintaining the solvent water content between about 2 and 10 wt. percent for refining naphthenic distillate.

In a specific application of this invention, a distillate naphthenic lubricating oil stock is separated from crude oil by vacuum distillation. The naphthenic oil stock is extracted in a single stage batch extraction operation

using N-methyl-2-pyrrolidone having varying water contents. The conditions and results are set forth below in Tables II, IIIA and Table IIIB:

EXAMPLE III

This example illustrates the advantage of water over aldehydes, ketones, glycols, sulfolane and organic acids as a solvent modifier for N-methyl-2-pyrrolidone refining of naphthenic lubricating oils. The conditions and results are set forth below in Tables III and IIIA. These data show that water will more effectively reduce the solvent power of N-methyl-2-pyrrolidone than will the other compounds.

¹ The S.O.D. Lead Corrosion Test is a bench test of corrosion resistance which is described in Military Specification MIL-L-708C, Lubricating Oil, Aircraft Turbine Oil, Synthetic Base, dated November 2, 1955 and is described in detail in U.S. Patent 3,003,963.

² The Heat Test is a bench test for thermal stability in which a 250 milliliter sample of the oil under test is heated for 125 hours at 250° F. and then held at room temperature for 1 day. The sample is then weighed to determine the evaporation loss, the viscosity is determined and compared with the oil before heating, the neutralization number is determined and the presence or absence of sludge is noted.

EXAMPLE V

This example illustrates the advantages of aqueous N-methyl-2-pyrrolidone over anhydrous furfural refining of naphthenic lubricating oil.

The example shows that a much lower solvent dosage

is required to make the same viscosity index raffinate (refined oil) with aqueous N-methyl-2-pyrrolidone than with anhydrous furfural. Additionally, a higher yield of refined oil is obtained with aqueous N-methyl-2-pyrrolidone at the same viscosity index level. The test data and results are reported below in Table V:

TABLE V

¹ N-methyl-2-pyrrolidone.

EXAMPLE VI

This example illustrates the unexpected aspects of the invention by a comparison of solvent refining of residual naphthenic and paraffinic lube oils under comparable conditions in a multistage countercurrent mixer-settler apparatus. That is the quality and yield of paraffinic oil can be controlled whereas that of the naphthenic oil cannot, unless water is added to N-methyl-2-pyrrolidone. The unrefined oil fractions employed were as follows:

35	Tests	Unrefined paraffinic oil	Unrefined naphthenic oil

EXAMPLE VII

A comparison of the solvent extraction characteristics of aqueous N-methyl-2-pyrrolidone with another gamma butyrolactam, aqueous 2-pyrrolidone, for lubricating oil refining is made by parallel batch extractions at the same conditions of a high viscosity residual lubricating oil stock and a similar comparison is made with an intermediate viscosity (vacuum distillate) lubricating oil stock. Both extractive solvents had a 2.5 and 5 wt. percent water content. It is found that 2-pyrrolidone is not as effective as N-methyl-2-pyrrolidone for the improvement of vis-

cosity index of lubricating oil stocks at the same conditions of temperature and dosage. A greater reduction in the refractive index of the refined oil is obtained with N-methyl-2-pyrrolidone and the reduction in refractive index in treating the high viscosity lubricating oil stock with N-methyl-2-pyrrolidone is greater than in treating the intermediate viscosity lubricating oil stock. The results are shown in Table VII and VIIA:

TABLE VII

15 We claim:

1. In the solvent refining of a naphthenic lubricating oil charge stock of a viscosity index of between about -10 and 50 for the removal of constituents having a low viscosity index, poor thermal stability and poor oxidation stability, the improvement which comprises contacting said lubricating oil stock with a wet solvent consisting essentially of between about 2 and 15 wt. percent water and between about 85 and 98% N-methyl-2-pyrrolidone at a temperature of at least 50° F. and below the temperature of complete miscibility of said lubricating oil stock in said wet solvent and at a dosage effective to dissolve at least 10 volume percent of said lubricating oil stock whereby a refined lubricating oil stock is produced of a viscosity index at least 10 units higher than the lubricating oil charge stock, and of improved thermal stability and improved oxidation stability.

2. The process of claim 1 wherein the solvent dosage is within the range of 30 and 300 volume percent, and the contacting temperature is within the range of 50 to 200° F.
